[57] CLAIM

The ornamental design for a telephone set, as shown and described.

DESCRIPTION

FIG. 1 is a perspective view of the front and upper surface and of the left side of a telephone set showing my new design;

FIG. 2 is a perspective view of the telephone set in opened position, showing the inner operative surfaces of the set's hinged components;

FIG. 3 is a front elevational view thereof, the rear elevational view being a mirror image;

FIGS. 4 and 5 are respectively top and bottom plan views thereof; and

FIGS. 6 and 7 are respectively right and left side elevational views thereof.

FIG. 1

FIG. 2

FIG. 4

FIG. 7

FIG. 3

FIG. 6

FIG. 5
